7 Claims. (Cl. 91—40)

The present invention relates to a control system and, more particularly, to a modification to a pressurized fluid control system of a type old and well known in the art.

It is old and well known to provide a pressurized fluid control system in which pressurized fluid impulse signals are supplied by a timing or programming device to a gating means, such as a fluid valve, for actuation thereof to selectively supply pressurized fluid to a fluid motor for reciprocating operation of a second mechanism between first and second extreme positions in synchronism with a first mechanism controlling or also being controlled by said programming device. However, it is sometimes desirable that operation of said first mechanism be permitted to continue while said second mechanism is actuated to and stopped in a position intermediate said extreme positions thereof as, for example, when repairs to such second mechanism are necessary. It is accordingly one object of the present invention to provide an arrangement of control apparatus, in a type of control system such as that discussed, which provides for relatively rapid actuation of said second mechanism to an intermediate position in response to a control signal and the stopping of such second mechanism in such intermediate position until the control signal is terminated.

Other objects and characteristic features of the invention will become apparent as the description proceeds.

In accomplishing the objects of the invention there is provided cam means which indicate the position which said second mechanism occupies at any point in time, and a plurality of gating means partially controlled by said cam means and at times actuated in response to a control signal to provide for actuation of such second mechanism to said intermediate position.

The invention will best be understood with reference to the single drawing figure which comprises a schematic diagram of a control system embodying the invention.

Referring to the drawing in detail, there is shown in block diagram form a first mechanism 10 which, as indicated in the conventional manner by the dotted line 11, controls or is controlled by a timing or programming device 12. The details of the mechanism 10 are not shown in the drawing since such mechanism may be any type of machine or device well known in the art and controlling or controlled by a programmer, such as 12.

Programmer 12 includes first and second cams 13 and 14 normally continuously rotating in a clockwise direction, as indicated by the arrows, thereon, and having cam lobes 16 and 17, respectively. Programmer 12 also includes first and second two-position pressurized fluid control valves 18 and 19 having plunger assemblies 21 and 22, respectively. Valves 18 and 19 are normally in first positions in which conductors or conduits 24 and 28 are respectively connected therethrough to fluid sinks 15 and 20, respectively, or to atmosphere if the pressurized fluid employed is compressed air, for example. Whenever the plunger assembly of the respective valve 18 or 19 is depressed by the respective cam lobe 16 or 17 during rotation of the cams 13 and 14, such valve is actuated to connect the respective conduit 24 or 28 to a conduit or conductor 23. Valves 18 and 19 are returned to their said normal positions by springs or by fluid pressure following an actuation thereof by the respective cam lobes 16 or 17, and when they are no longer depressed by their respec-

tively associated cam lobes. Programmers or timing devices such as 12, and valves such as 18 and 19 are well known and no further detailed discussion thereof is believed necessary. Pressurized fluid from a source thereof is provided over said conductor or conduit 23 to said control valves 18 and 19. Such fluid source is not shown in the drawings for purposes of simplification thereof; however, such pressurized fluid may, for example, be compressed air.

When valve 18 is actuated to its on position, the pressurized fluid supplied thereto from conductor or conduit 23 is permitted to flow through conductor or conduit 24 and through a restriction 26 to one end of a two-position, four-way gating means or valve 27. Similarly, when valve 19 is actuated to its on position, the pressurized fluid supplied thereto from conductor 23 is permitted to flow through conductor or conduit 28 and through a restriction 25 to the other end of said gating means 27. As will be further discussed hereinafter in this description, gating means 27 alternates the flow of pressurized fluid from a source thereof to conductors or conduits 29 and 31, and thence to first and second ends of a reciprocating pressurized fluid motor 32, in accordance with said permitted flow of pressurized fluid through conductors 24 and 28 to said ends of gating means or valve 27. Gating means or valves, such as 27, and reciprocating fluid pressure motors, such as 32, are well known and no further detailed discussion thereof is believed necessary.

Fluid pressure motor 32 includes the usual piston rod 33 which is connected in any convenient manner to the previously mentioned second mechanism, such second mechanism being shown as including a rack 34 and a pinion gear 36 each having gear teeth in cooperative intermeshing engagement, as in the usual arrangement of rack 34 and pinion gears. It will be readily apparent that rack 34 and pinion gear 36 are reciprocatively actuated between first and second extreme positions in accordance with the reciprocating actuation of piston rod 33 of pressurized fluid motor 32.

The apparatus or control system thus far described is old and well known and the apparatus hereinafter described is the inventive modification to such old apparatus, that is, the apparatus hereinafter described is the new apparatus or the modification embodying the invention.

As indicated in the conventional manner by the dotted line 37, cam means comprising cam wheels 38 and 39 are connected to pinion gear 36 for corresponding driven rotation of such wheels by such gear. That is, when pinion gear 36 is driven by rack 34 in a clockwise direction, as indicated by the arrow, cam wheels 38 and 39 are correspondingly driven in such direction, as indicated by the arrows on such wheels. Likewise, when gear 36 is driven in a counterclockwise direction by rack 34, wheels 38 and 39 are correspondingly driven in a counterclockwise direction.

Associated with cam wheel 38 is a cam follower 41 having a roller 42 pivotally mounted on one end thereof and bearing against the outer periphery of cam wheel 38. The other end of cam follower 41 is connected to a two-position, four-way gating means or valve 43 to be hereinafter discussed. Said outer periphery of cam 38 is provided with a recessed portion 48 which is located on such outer periphery so as to correspond to the previously-mentioned intermediate position of said second mechanism, that is, of said rack and pinion gear 34—36. The location and purpose of such recessed portion 48 will be further discussed hereinafter.

There is associated with cam wheel 39 a cam follower 44 having a roller 46 pivotally mounted on one end thereof and bearing against the outer periphery of cam wheel 39. The other end of cam follower 44 is connected to a three-position three-way gating means or valve 47 to

be hereinafter discussed. Said outer periphery of cam wheel 39 is provided with two recessed portions, that is, two portions of lesser radii than the remainder of the wheel. A first of such recessed portions is indicated by the reference character 49 and extends about the outer periphery of cam wheel 39 a distance slightly less than, but substantially corresponding to the arc of rotation of such cam wheel when pinion gear 36 rotates between said intermediate position and its said first extreme position. The second of said recessed portions is indicated by the reference character 51 and extends about the outer periphery of cam wheel 39 a distance slightly less than, but substantially corresponding to the arc of rotation of such cam wheel when pinion gear 36 rotates between said intermediate position and its said second extreme position. The radius of recessed portion 49 is intermediate the radius of the outer periphery of cam wheel 39 and the radius of recessed portion 51. The peripheral extent of recessed portions 49 and 51 and the purposes of such recessed portions will be made more apparent hereinafter in an operational example of the apparatus of the invention.

As previously mentioned, gating means or valve 43 is a two-position, four-way valve. Such valve is located intermediate the source of the pressurized fluid used for the actuation of fluid motor 32 and is provided to permit or interrupt, as hereinafter discussed, the flow of pressurized fluid to such motor. As also previously mentioned, gating means or valve 47 is a three-position, three-way valve. Such valve is used to control a supply of pressurized fluid for supplemental operation of the previously discussed gating means or valve 27, and supplemental operation of fluid motor 32, as hereinafter discussed.

An additional gating means or valve 52 is also provided, such gating means comprising a two-position, three-way valve which is normally maintained in a first position by a compression spring 53 connected thereto. Such gating means or valve is shown as an electrical solenoid valve which is actuated to its second position when the control winding 54 thereof is energized, and is returned to its normal position by spring 53 when control winding 54 is again deenergized following a period of energization thereof.

A plurality of manually operated electrical switches 56 and 57 provide for the closing of electrical circuits for the energization of the control winding 54 of solenoid valve 52. Such switches may be located adjacent or remote from the remainder of the apparatus, as desired. Switches 56 and 57 are of the type which remain in their open or closed positions to which they are manually actuated until a following manual actuation thereof changes them to their opposite positions. A first energizing circuit for control winding 54 extends from terminal X of a source of electrical current of suitable voltage and capacity, over the contacts of switch 56 in its closed position and thence through said control winding to terminal Y of said current source. A second energizing circuit for said control winding extends from terminal X of said current source, over the contacts of switch 57 in its closed position and thence through control winding 54 to terminal Y of said current source. For purposes of simplification of the drawings, said source of current is not shown therein.

Gating means or valve 52 is employed to provide control signals to valves 47, 43 and 27, such control signals being preferably in the form of pressurized fluid signals. However, it is pointed out that such valves or gating means could be electrical solenoid actuated valves and said control signals would, of course, then be electrical signals. It is also pointed out that gating means or valve 52 could be a valve which is actuated by pressurized fluid supplied thereto from one or more remote locations by the actuation of manually operable pressurized fluid control valves provided at such locations. Furthermore, one or more manually operated pressurized fluid control valves could obviously be substituted for valve 52 and its associated electrical control switches 56 and 57.

It is believed that the apparatus arrangement shown in the drawing will now best be understood by reference to the operational examples of the invention which follow.

For the purpose of describing the operation of the apparatus, it will be assumed that the reciprocative action of pinion gear 36 is through a 180° arc of rotation, such actuation of the pinion gear being provided by the reciprocating actuation of pressurized fluid motor 32 and the resultant corresponding actuation of rack 34. It will be further assumed that the intermediate position at which it is at times desired to stop said actuation of pinion gear 36 is midway between the two extreme positions of said 180° arc of rotation. It is also pointed out that the apparatus is illustrated in the drawing in the positions occupied thereby when pinion gear 36 has been actuated to its extreme clockwise position.

At some point in time following the actuation of pinion gear 36 to its extreme clockwise position as mentioned above, cam 14 of programmer or timing device 12 causes its associated cam lobe 17 to momentarily depress the plunger assembly 22 of valve 19 thereby supplying pressurized fluid through conductor 28 and through restriction 25, to be hereinafter further discussed, to the right hand side, as shown in the drawing, of gating means or valve 27. Such pressurized fluid actuates gating means or valve 27 to the position opposite from that illustration and pressurized fluid is then supplied through valve 43 and through conductor or conduit 60 to valve 27, and thence through conductor or conduit 29 to the right hand side, as illustrated in the drawing, of fluid motor 32. The pressurized fluid at such time actuates motor 32 to move its piston rod 33 and, thereby, rack 34 to the left and cause counterclockwise rotation of pinion gear 36. The pressurized fluid in the left hand side of motor 32 flows, at such time, through conductor 31 to gating means or valve 27, and thence through conductor 61 to gating means or valve 43 and to a fluid sink 63, or to atmosphere if the pressurized fluid employed is, for example, compressed air. No other actuation of the apparatus takes place during such operation, except it is pointed out that cams 38 and 39 are correspondingly moved in a counterclockwise direction by said rotation of pinion gear 36.

At some point in time following the above described counterclockwise rotation of pinion gear 36, cam 13 of programmer 12 causes its associated cam lobe 16 to momentarily depress plunger assembly 21 of valve 18 thereby supplying pressurized fluid to conductor 24 and through restriction 26, to be hereinafter further discussed, to the left hand side of gating means or valve 27. Such pressurized fluid reactuates valve 27 to the position shown in the drawings to again alternate the supply of pressurized fluid to motor 32. The flow path for the pressurized fluid at such time is over conductor or conduit 60, through valve 27 to conductor or conduit 31 and thence to the left hand side of motor 32. Such fluid again actuates the piston rod 33 and, thereby, rack 34 to the right as illustrated. Pinion gear 36 and cams 38 and 39 are thereby rotated in their clockwise directions. The fluid in the right hand side of motor 32 at such time flows through conductor or conduit 29 and valve 27, and thence through conductor 61 and valve 43 to sink 63 or to atmosphere, as previously mentioned. It is thus apparent that, normally, rack 32 and pinion gear 36, comprising the previously mentioned second mechanism, are actuated in predetermined synchronism with the first mechanism 10, such first mechanism controlling the programming cycles of programmer 12 or also being controlled by such programmer as the case may be.

It will now be assumed that it is desired to actuate pinion gear 36 to its aforesaid intermediate position and to stop such device in that position. Accordingly, one of the manually actuated switches 56 or 57 is operated to its circuit closing position and the control winding 54 of solenoid gating means or valve 52 is energized to ac-

tuate such valve to the position opposite from that shown in the drawing. Following such actuation, pressurized fluid is supplied through such valve to conductor or conduit 65 and thence to conductors or conduits 66, 67 and 68. If pinion gear 36 is in either of its extreme positions at such time, no further actuation of the apparatus takes place immediately, since roller 46 associated with cam follower 44 bears against a region of the large outer periphery of cam 39, such as illustrated. However, assuming at the time of actuation of valve 52 that the apparatus is in the condition illustrated in the drawing, following the normal actuation of valve 19 of programmer 12 to initiate the counterclockwise rotation of pinion gear 36, roller 46 and cam follower 44 are permitted to move to the right so that such roller contacts the portion 49, of cam wheel 39, having a smaller radius. Gating means or valve 47 is, therefore, actuated at such time, by the pressurized fluid supplied to the left hand side thereof over conductor 67, to supply the pressurized fluid supplied to conductor or conduit 66 through valve 47 to conductor or conduit 71 and thence to the right hand side of valve 27. However, such supply of pressurized fluid has no effect at such time since valve 27 has previously been actuated to reverse the supply of pressurized fluid to motor 32. Accordingly, pinion gear 36, and cam wheels 38 and 39, continue to move in a counterclockwise direction until the pressurized fluid supplied to conductor or conduit 68 can actuate valve 43 to terminate the supply and drain of pressurized fluid to and from motor 32. Such termination occurs when the recessed portion 48 of cam wheel 38 reaches the point where cam follower 41 is permitted to move to the right to move its associated roller 42 into such recess. Pinion gear 36 occupies its said intermediate position at such time and said termination of pressurized fluid flow to and from motor 32 stops the motor and, thereby, pinion gear 36 in such intermediate position. Subsequent to the stopping of pinion gear 36, programmer 12 continues to periodically actuate valves 18 and 19, but the pressurized fluid supplied by valve 47, to the right hand side of valve 27, prevents actuation of valve 27 when pressurized fluid is supplied, by the actuation of valve 18, to the left hand side of valve 27.

Assuming now, at the time of the aforesaid actuation of valve 52, that the apparatus is in its other extreme condition, that is, opposite to that illustrated in the drawing, following the normal actuation of valve 18 of programmer 12 to initiate the clockwise rotation of pinion gear 36, roller 46 and cam follower 44 are permitted to move to the right so that such roller contacts the portion 51, of cam wheel 39, having the smallest radius. Gating means or valve 47 is, therefore, actuated at such time, by the pressurized fluid supplied to the left hand side thereof over conductor 67, to supply the pressurized fluid, supplied to conductor or conduit 66 through valve 47, to conductor or conduit 72 and thence to the left hand side of valve 27. However, such supply of pressurized fluid has no effect at such time since valve 27 has previously been actuated to reverse the supply of pressurized fluid to motor 32. Accordingly, pinion gear 36 and cam wheels 38 and 39 continue to move in a clockwise direction until the pressurized fluid supplied to conductor or conduit 68 can actuate valve 43 to terminate the supply and drain of pressurized fluid to and from motor 32. Such termination occurs when the recessed portion 48 of cam wheel 38 reaches the point where cam follower 41 is permitted to move to the right to move its associated roller 42 into such recess. Pinion gear 36 occupies its said intermediate position at such time and said termination of pressurized fluid flow to and from motor 32 stops the motor and, thereby, pinion gear 36 in such intermediate position. Subsequent to the stopping of pinion gear 36, programmer 12 continues to periodically actuate valves 18 and 19, but the pressurized fluid supplied by valve 47 to the left hand side of valve 27 prevents actuation of valve 27

when pressurized fluid is supplied by the actuation of valve 19 to the right hand side of valve 27.

If pinion gear 36 is moving in a counterclockwise direction between its first extreme position and its intermediate position when a control signal is supplied from valve 52 to conductor or conduits 65, operation of the apparatus similar to that first described above occurs, that is, pinion gear 36, and cam wheels 38 and 39, continue to move in a counterclockwise direction until such gear is stopped in its intermediate position in the manner above described. Similarly, if pinion gear 36 is moving in a clockwise direction between its second extreme position and its intermediate position when a control signal is supplied from valve 52 to conductor or conduit 65, operation of the apparatus similar to that secondly described above occurs, that is, pinion gear 36, and cam wheels 38 and 39, continue to move in a clockwise direction until such gear is stopped in its intermediate position.

Assuming now that pinion gear 36 is moving in its counterclockwise direction and is between its intermediate position and its second extreme position, the following operation occurs upon the supply of a control signal, at such time, to conduit 65. It will be noted that, at such time, valve 27 is in the position of supplying pressurized fluid to the right hand side of motor 32 for the counterclockwise actuation of pinion gear 36. It is, therefore, necessary to actuate valve 27 to reverse the supply of fluid to motor 32 and return pinion gear 36 clockwise to its intermediate position. Accordingly, the control signal or pressurized fluid supplied to conduit 65 flows through conduit or conductor 67 to actuate valve 47 to supply the pressurized fluid, supplied to conductor 66 from conduit 65, to conduit 72. Cam wheel 39 is in a position, at such time, to permit the full movement of cam follower 44 and said actuation of valve 47. At such time, the pressurized fluid supplied to conductor or conduit 72 is, therefore, supplied to the left hand end of valve 27 to actuate such valve to reverse the connections to conduits 29 and 31, and thereby actuate motor 32 to stop the counterclockwise rotation of pinion gear 36 and rotate it clockwise towards its intermediate position. Upon reaching said intermediate position, the pressurized fluid supplied to conductor or conduit 68 from conduit 65 operates valve 43, in the manner previously described, to terminate fluid flow to and from motor 32, and pinion gear 36 stops in its intermediate position.

If pinion gear 36 is moving in its clockwise direction and is between its intermediate and its first extreme position, the following operation occurs upon the supply of a control signal, at such time, to conduit 65. It will be noted that, at such time, valve 27 is in the position of supplying pressurized fluid to the left hand side of motor 32 for the clockwise actuation of pinion gear 36. It is, therefore, necessary to actuate valve 27 to reverse the supply of fluid to motor 32 and return pinion gear 36 counterclockwise to its intermediate position. Accordingly, the control signal or pressurized fluid supplied to conduit 65 flows through conduit 67 to actuate valve 47 to supply the pressurized fluid, supplied to conductor 66 from conduit 65, to conduit 71. Cam wheel 39 is in a position, at such time, to permit only partial movement of cam follower 44 and said actuation of valve 47. At such time, the pressurized fluid supplied to conduit 71 is supplied to the right hand end of valve 27 to actuate such valve to reverse the connections to conduits 29 and 31, and thereby actuate motor 32 to stop the clockwise rotation of pinion gear 36 and rotate it counterclockwise toward its intermediate position. Upon pinion gear 36 reaching its intermediate position, the pressurized fluid supplied to conduit 68 from conduit 65 operates valve 43, in the manner previously described, to terminate fluid flow to and from motor 32. Pinion gear 36 is thereby stopped in its intermediate position.

It will be noted that when valve 43 is actuated to terminate fluid flow to and from motor 32 as described

above, such motor will not again be actuated until valve 43 is reactuated to permit the flow of pressurized fluid to motor 32. It is also apparent that the reactivation of motor 32 and the resultant operation of pinion gear 36, following a period of stopping thereof, should be accomplished so that pinion gear 36 is again operated in synchronism with the operation of the first mechanism 10 which perhaps was permitted to continue its operation during said period of the stopping of motor 32 and pinion gear 36. Accordingly one end of a conductor or conduit 73 is connected to conductor or conduit 24 between restriction 26 and valve 18 of programmer 12, the other end of conduit 73 being connected to the right hand side of valve 43. When it is desired to again start the operation of motor 32 and the second mechanism (rack and pinion gear 34-36) following a period of stopping thereof, the respective manually operated switch 56 or 57 which was previously operated to its circuit closing position to cause the actuation of pinion gear 36 to and the stopping thereof in its intermediate position, is operated to its open position. The winding 54 of gating means or valve 52 thus becomes deenergized and compression spring 53 returns valve 52 to its normal position shown in the drawing. The supply of pressurized fluid to conductor or conduit 65 is thereby interrupted and such conduit is connected to a fluid sink 74, or to atmosphere if the pressurized fluid is, for example, compressed air. Such actuation of valve 52 relieves the pressure supplied to conduits 65, 66, 67 and 68, and when valve 18 of programmer 12 is actuated by such programmer to supply an impulse signal to conduit 24, such signal is supplied to the left hand side of valve 27 and also, through conduit 73, to the right hand side of valve 43. Such signal actuates valve 27 to its position shown in the drawing, if such valve 27 does not already occupy such position, and also actuates valve 43 to its normal fluid-flow position shown. Such actuation of valves 27 and 43 permits pressurized fluid to flow to and from the left and right hand sides, respectively, of motor 32. Motor 32 is thus actuated to cause rotation of pinion gear 36 in its clockwise direction again starting its reciprocative operation in synchronism with programmer 12 and first mechanism 10.

It is pointed out at this time that restrictions 25 and 26 are provided to assure operation of valve 27 when pressurized fluid is supplied to the right and left hand sides, respectively, of such valve through conduits 71 and 72, respectively. Said restrictions, at such times, restrict the flow of fluid from conduits 71 and 72 to conduits 28 and 24, respectively. It is also pointed out that, following an actuation of valve 47 by a control signal supplied to conduit 67, valve 47 is not returned to its normal position shown in the drawing until pinion gear 36 is actuated to its first extreme position, that is, to the position at the end of the clockwise rotation of pinion gear 36. At such time cam wheel 39 presses against roller 46 and actuates cam follower 44 to return valve 47 to its normal position shown in the drawing.

It should also be pointed out that the valves 27, 43, 47 and 52 are shown in the drawings in a conventional manner, and that any suitable type of valve, such as for example spool type valves, may be used for such valves. If spool type valves are employed for valves 43 and 47, the cam followers 41 and 44 may be connected to the spools of the respective valves to prevent or permit the actuation of such valves in the manner hereinbefore described.

Although there is herein shown and described only one form of apparatus for practicing the invention, it will be understood that various changes and modifications may be made therein within the scope of the appended claims without departing from the spirit and scope thereof.

What is claimed is:

1. In a control system in which first and second impulse signals are alternately supplied in synchronism with a first actuated mechanism and through first and second conduc-

tors, respectively, to a first signal responsive gating means for alternation of the flow of pressurized fluid supplied from a source thereof to a fluid pressure motor connected to reciprocatively actuate a second mechanism between first and second extreme positions, respectively, in accordance with said alternation and in a timed relationship with said first mechanism; apparatus for at times actuating said second mechanism to a position intermediate said extreme positions and for stopping such mechanism in such intermediate position, such apparatus comprising, in combination, cam means actuated in synchronism with said second mechanism, three-position second gating means normally in a first position and at different times actuatable in response to a control signal to second or third positions; a first cam follower associated with said cam means and said second gating means for permitting actuation of such gating means to its said second or third positions in response to said control signal according as said second mechanism is between said intermediate position and said first or said second extreme positions, respectively, and for returning the second gating means to its said first position when such gating means is in other than such first position and said second mechanism moves into one of its said extreme positions; two-position third gating means normally in a first position and at times actuatable in response to a control signal to a second position, said gating means inserted intermediate said pressurized fluid source and said fluid motor and permitting or interrupting flow of said fluid according as such gating means is in its said first or second positions, respectively; a second cam follower associated with said cam means and said third gating means for permitting actuation of such third gating means to its said second position in response to said control signal only when said second mechanism is in its said intermediate position; a manually actuatable gating means for supplying when actuated, a control signal to said second and third gating means; means controlled by said second gating means for supplying a control signal to said first gating means through said first or second conductors when said manual gating means is actuated and such second gating means is in its said second or third positions, respectively; and means connecting said first conductor and said third gating means for supplying said first impulse signal to such third gating means for reactivating such gating means to its said first position when it is in its said second position and said control signal supplied thereto is terminated.

2. Apparatus, in accordance with claim 1, in which said signals are pressurized fluid signals and said gating means are fluid flow control valves.

3. Apparatus, in accordance with claim 2, in which said pressurized fluid signals are supplied from a source of compressed air.

4. In a control system in which a fluid pressure motor is connected to reciprocatively operate a second mechanism between first and second positions in a timed relationship with a first mechanism in accordance with first and second impulse signals alternately supplied in synchronism with said first mechanism to first and second ends of a first signal responsive valve for alternation of the flow of pressurized fluid from a source thereof to said motor and, thereby alternation of the operation of such motor; a modification to said control system for at times actuating said second mechanism to a position intermediate said first and second positions and for stopping such mechanism in such intermediate position, such modification comprising, first and second cam means operated in synchronism with said second mechanism; a second control valve normally permitting said flow of pressurized fluid to said motor and controlled by said first cam means so as to be actuatable in response to a control signal for interrupting such flow only when said second mechanism is in its said intermediate position, a third control valve controlled by said second cam means so as to be actuatable in response to a control signal to supply a control signal to said first or second ends of said first valve according as said second

mechanism is between said intermediate position and said first position, or between such intermediate position and said second position, respectively; manual control means for supplying said control signals to said valves; and means for supplying one of said impulse signals to said second valve for reactuation thereof to again permit said fluid flow to said motor following a period of interruption of such flow by the actuation of such valve in response to a control signal, such impulse signal being effective to reactuate the valve only following the termination of said control signal.

5. Apparatus, in accordance with claim 4, in which said pressurized fluid comprises a liquid under pressure.

6. Apparatus, in accordance with claim 4, in which said signals are pressurized fluid signals.

7. Apparatus, in accordance with claim 6, in which said pressurized fluid signals are compressed air signals.
